UNITED STATES PATENT OFFICE.

JOHN P. MINTON, OF EAST ORANGE, NEW JERSEY, AND CHARLES A. FINLEY, OF BROOKLYN, NEW YORK, ASSIGNEES TO WESTERN ELECTRIC COMPANY, INCORPORATED, OF NEW YORK, N. Y., A CORPORATION OF NEW YORK.

TELEPHONE TRANSMITTER.

Application filed March 27, 1918. Serial No. 224,981.

To all whom it may concern:

Be it known that we, JOHN P. MINTON and CHARLES A. FINLEY, citizens of the United States, residing at East Orange, in the county of Essex and State of New Jersey, and at Brooklyn, in the county of Kings and State of New York, respectively, have invented certain new and useful Improvements in Telephone Transmitters, of which the following is a full, clear, concise, and exact description.

This invention relates in general to telephone transmitters, and more specifically to a transmitter particularly suitable for use in places subjected to severe extraneous noises or to vibrations set up by the rush of wind.

In many cases it is important that a transmitter be provided which will be sensitive and efficient in operation and yet one which will not be interfered with by excessive noises or violent explosions occurring close by. Such are the requirements, for example, for a transmitter to be used in connection with telephone sets on aeroplanes for communication between the pilot and the observer or for wireless communication with other stations. Under such conditions the violent disturbances set up by the exhaust of the engines and the rush of air make direct audible conversation impossible, and it has been necessary to resort to the use of telephones for communication. However, to obtain satisfactory transmission it has heretofore been necessary to shield the transmitter by mounting it in a practically sound proof box into which the user must thrust his face when talking. Such an arrangement is not only awkward and cumbersome but is quite likely to interfere with the other duties of the user, as well as obstruct his vision. Again, for use with fire control on battleships or land fortifications, there is a decided need for a transmitter which will easily and intelligibly transmit speech in spite of the violent concussions due to the discharge of batteries nearby.

It is therefore the object of the present invention to provide a telephone transmitter which will not be susceptible to the disturbing noises or whistling resulting from the action of the wind when the transmitter is exposed in the open, or to the rush of air

when mounted on an aeroplane or similar device traveling at high speed.

A further object is to provide a transmitter which will not be affected by violent extraneous noises occurring nearby.

A still further object is to provide a transmitter meeting the above requirements and one which will be efficient in transmission, cheap of manufacture and which will be free from all delicate adjustments necessitating expert attention.

To accomplish the above objects a feature of the present invention resides in equipping a transmitter with a face plate in which are provided a plurality of holes or perforations small in diameter.

Another feature consists in providing a very small resonating chamber, that is, making the clearance between the diaphragm and the face plate very small to further aid in preventing outside disturbances affecting the diaphragm.

Other objects and features of the invention will be apparent from the following description, and will be particularly pointed out in the appended claims.

The invention is illustrated in the accompanying drawing in which Fig. 1 is a sectional view of a transmitter embodying this invention; and Fig. 2 is a front view of the transmitter shown in Fig. 1 and having a portion of the face plate removed to more clearly show the internal construction.

Referring now to the drawing, there is provided a casing 5 to which the face plate 6 is secured by means of screws 7-7. Since the face plate and casing are preferably made of aluminum, it has been found advisable to employ shouldered studs 8-8 of German silver or similar material and threaded to receive the screws 7-7. The ring 9 is clamped between the face plate 6 and the casing 5. The face plate 6 is perforated with a large number of evenly distributed perforations 10-10 which are small in diameter in comparison with the thickness of the face plate. In practice, it has been found that very satisfactory results are obtained when the diameter of these perforations is .050 inches or less, and the thickness of the face plate is not less than one-eighth of an inch. The inner side of the face plate is counterbored to receive the dia-

phragm 12 and the spacing ring 13 which is preferably of oiled linen. This spacing washer 13, which is very thin, determines the size of the resonating chamber formed between the face plate 6 and the diaphragm 12, and into which the perforations 10 lead directly. In practice, a resonating chamber of .015 inches or less is found to give very satisfactory operation, such a chamber being resonant to vibrations having the frequency of useful voice currents and also acting efficiently to prevent violent vibrations in the air from affecting the diaphragm. Centrally located at the rear of the casing 5 is the shouldered bridge center 14, which is held in place by the lock nut 15, and is insulated from the casing by means of the mica washers 16 and 17 and the insulating bushing 18. Located between the shouldered portion of the bridge center 14 and the mica washer 17 is a metal plate 19 having an extended portion provided with the terminal screw 20. The bridge center is bored out to receive the shank 21 of a standard type of transmitter button comprising a cup member 22 in which are located the front electrode 23 and back electrode 24, the remainder of the space being practically filled with granular carbon which is held in place by means of the mica annulus 25 and the retaining nut 26. The front stud 27, which is in direct electrical contact with the front electrode, is held firmly against the center of the diaphragm 12 by the tension of spring 28. This spring is secured to the casing 5 by means of screws 29-29 and plate 30, a portion of the clamping ring 9 being recessed as at 31 to provide the necessary clearance. After the transmitter has been assembled and the button properly located by the tension of spring 28, the button is locked in position by tightening screw 32 which is threaded into the bridge center 14 and bears against the shank 21 of the transmitter button. A screw 33 is threaded directly into the casing 5 to serve as the terminal screw for the front electrode.

It will be noted that in the structure as illustrated and described the entire casing is employed as a bridge member to support the shank of the transmitter button instead of employing the lighter type of bridge commonly used. This construction provides a very rigid support for the transmitter button, thereby resulting in greater efficiency and improved quality of transmission. The transmission of the voice sound waves is decreased but slightly by the comparatively small openings in the face plate; but these openings, however, are very efficient in preventing the vibrations set up by violent explosions or loud noises from affecting the diaphragm. Such vibrations are further prevented from causing disturbances by the extremely small resonating chamber. While

face plates have been used heretofore provided with a plurality of openings, such arrangements have been provided entirely with the idea of protecting the transmitter from mechanical injury and preventing the entrance of dust. In all cases these face plates have been comparatively thin and the holes of such dimensions as to be of no advantage in preventing the vibrations from violent explosions affecting the diaphragm. As a still further aid in preventing such disturbance from interfering with transmission, the transmitter button is filled practically full with granular carbon, thereby making a button which is less microphonic and consequently less affected by the external vibrations although somewhat less efficient in transmission. To offset this loss in efficiency the customary mouthpiece is omitted, thereby permitting the user to talk closer to the diaphragm. A diaphragm is also used so dimensioned and clamped that it has a high natural period above that of the useful voice waves. This arrangement not only provides a more efficient and uniform operation at voice frequencies and a better quality of transmission, but also is less sensitive to mechanical vibration, and to the lower frequencies such as occur in the majority of cases from outside disturbances. The absence of the customary transmitter mouthpiece not only prevents a certain amount of whistling which would otherwise result from the action of the wind, but also eliminates that resonating chamber which would magnify all disturbing vibrations.

What is claimed is:

1. In a transmitter, a diaphragm, a face plate having a perforation therethrough, the diameter of said perforation being less than the thickness of the face plate and a thin resonating chamber communicating with said perforation.
2. In a transmitter, a diaphragm, a face plate having a plurality of perforations extending therethrough, the diameter of said perforations being less than the thickness of the face plate and a thin resonating chamber between said diaphragm and face plate communicating with the perforations in the face plate.
3. In a transmitter, the combination with a diaphragm of a face plate, means in said face plate to permit the diaphragm being actuated by speech vibrations and to prevent its being actuated by violent vibrations of the air, and additional means for further preventing the diaphragm from being actuated by violent vibrations of the air.
4. In a transmitter, a face plate not less than one-eighth inch in thickness, having a plurality of perforations therethrough, said perforations being perpendicular to the plane of said diaphragm and not greater than .050 inches in diameter.

5. In a transmitter, a face plate having a plurality of small openings therethrough, the diameter of said perforations being less than the thickness of the face plate; and a 5 diaphragm spaced adjacent thereto but separated therefrom to provide a thin resonating chamber having a depth not greater than .015 inches communicating with the openings in said face plate.
- 10 6. In a transmitter, a casing, a transmitter button having a cup member in which are located the front and back electrodes practically filled with granular carbon, means for supporting said button in said casing, a 15 diaphragm having a high natural period, spring means for maintaining said button in engagement with said diaphragm, and a face plate having a plurality of small openings whereby violent vibrations of air exterior 20 nal to the transmitter are prevented from actuating said diaphragm.
7. A transmitter comprising a face plate, a diaphragm mounted in face-to-face relation with said plate, and means including a plurality of small and relatively deep perforations through said plate offering a large amount of surface friction to the passage of pressure variations therethrough to shield the diaphragm from sudden and violent pressure changes. 25
8. A transmitter comprising a cup, a relatively thick flat plate forming a cover for said cup, a diaphragm mounted in close face-to-face relation to said plate within said cup, and a plurality of relatively small perforations of uniform depth extending through said plate. 30

In witness whereof, we hereunto subscribe our names this 25th day of March, A. D., 1918.

JOHN P. MINTON.
CHARLES A. FINLEY.
